CLAIM

The ornamental design for a combined cup and cell phone holder for molded plastic chair, as shown and described.

DESCRIPTION

FIG. 1 is a perspective view of our combined cup and cell phone holder for molded plastic chair;

FIG. 2 is a top view thereof;

FIG. 3 is a left side view thereof;

FIG. 4 is a right side view thereof;

FIG. 5 is a front view thereof;

FIG. 6 is a rear view thereof;

FIG. 7 is a bottom view thereof;

FIG. 8 is a perspective view, drawn at a smaller scale than FIGS. 1 through 7, showing our combined cup and cell phone holder for molded plastic chair on the arm of a molded plastic chair.

FIG. 9 is a perspective view, drawn at the same smaller scale as FIG. 8, showing our combined cup and cell phone holder for molded plastic chair attached to the underside of the arm of a molded plastic chair.

FIG. 10 is a top view of an alternative embodiment of our combined cup and cell phone holder for molded plastic chair; and,

FIG. 11 is a bottom view of the embodiment shown in FIG. 10; the left side, right side front and rear views of this embodiment being the same as comparable views of the first embodiment shown in FIGS. 3-6.

The portion of the chair in dash-dot lines in FIGS. 8 and 9 and the optional oval cut-out shown in in dash-dot lines in FIGS. 10 and 11 are shown for environmental purposes and form no part of the claimed design.
